UNITED STATES PATENT OFFICE.

HENRI FONTY, OF PARIS, FRANCE, ASSIGNOR TO SOCIÉTÉ ANONYME DES ÉTABLISSEMENTS LEFLAIVE, JEAN JACQUES KNECHT, OF PARIS, FRANCE.

BOBBIN CARRIER FOR LACE-BRAIDING MACHINES.

Application filed November 9, 1925. Serial No. 67,954.

To all whom it may concern:

Be it known that I, HENRI FONTY, a citizen of the French Republic, residing at Paris, Department of the Seine, in France, have invented certain new and useful Improvements in Bobbin Carriers for Lace-Braiding Machines, of which the following is a specification.

This invention relates to a novel bobbin-carrier for lace-braiding machines; which permits the use of a larger bobbin, holding twice or four times as much thread as the bobbin-carriers now in use. The stirrup usually located at the side of the bobbin and extending beyond it, which carried the devices for guiding and stopping the thread, is eliminated and replaced by a fixed member, a kind of cap, upon which are arranged the thread guiding and stopping devices.

This device permits the rapid exchange of the bobbins. The device is balanced and arranged in such way that its center of gravity is always intersected by the axis of the bobbin-carrier, whereby when the machine is running, the rotation of the bobbin-carrier about its axis is obviated, thus preventing any twisting or untwisting of the thread. Moreover, this device provides an abutment for the bobbin towards the top, preventing it from coming off under the action of the tension of the thread and from interfering with the operation of the stopping device. By eliminating the stirrups, the space between the spindles of the bobbin-carriers

is completely available for the bobbins, thus permitting the amount of thread on the bobbins to be increased, consequently there are fewer stops, less time wasted and greater output.

The accompanying drawing shows by way of example one construction of the bobbin-carrier in accordance with the invention. In the drawing:

Figure 1 is an elevation of three adjacent bobbins on their respective carriers, the middle one being shown provided with the new device.

Fig. 2 is a plan of said device.

Fig. 3 is a horizontal section taken on line 3-3 of Figure 1.

Referring to the drawing, 1 are the hollow spindles of the bobbin-carriers on which turn freely the bobbins 2 filled with thread and provided at the top with ratchet discs 2^a as usually employed and intended for

stopping the thread. These bobbins 2 when used with my invention, may be filled until they almost touch at their peripheries, or in the case of a pole thread leave place for the tube 3 between them. The 60 stirrup hitherto employed, which was fixed on the spindle 1 at the position of the ring 4 is eliminated. The devices for guiding and stopping the thread, which were carried by said stirrups are in this invention attached 65 to a sort of cap 5 (Figures 1 and 2), which is located above the bobbin at the upper part of the spindle 1. The lever 6 is pivoted on the cap and carries a pawl 6^a which extends through a hole 6^b in the cap and engages the ratchet disk 2^a to prevent the bobbin from rotating in one direction. This lever is joined to a hinge constituted by the angle iron 7, which serves to guide the thread. Another thread-guide 8, consisting 70 of a weak spring directed downwards, is also attached to the cap 5 and it takes up the thread as it unwinds and directs it upwards. A third thread-guide 9, is attached to the tubular part 5^a of the cap 5, and is 75 directed diametrically opposite to the guide 7, so as to secure equilibrium. The guide 9 leads the thread towards the center of the machine.

This guide 9 serves two purposes: 85

1. That of directing the bobbin-carrier and preventing it from rotating on its axis, for which a slight tension of the thread is sufficient.

2. That of preventing contacts due to the 90 hooking of the thread by the ends 10 of the adjacent bobbin-carriers, as well as by the ends 10' of the tube of the pole thread (see Fig. 1). These ends 10 are usually constituted by a porcelain eye and may be attached either to the cap tube 5^a or to the spindle 1.

The position and direction of the cap 5 with respect to the spindle are determined by a special device, which in the example 100 chosen consists of a leaf spring 11 attached to the cap and hooking by means of two jaws 12 into the notch 13 of the spindles 1. A set screw or a split ring would serve the same purpose, but more time would then be required to lift off the bobbins and change them, whilst with the device described, it suffices to push the spring 11 in the direction shown by the arrow to disengage the jaws 12 from the notch 13. The 110

tubular part 5^a of the cap is slotted to permit the jaws to engage the notch 13. Two guiding members 14 mounted on the tube 5^a prevent any bending of the spring 11 in a vertical direction, and consequently they fix the position of the cap 5 with respect to the notch 13 in the spindle 1.

The thread coming from the bobbin passes through a hole in the end of the 10 spring 8, then through another provided in the end of the angle iron 7. It subsequently passes through an eye 6^c in the lever 6 and thence down inside the spindle 1, where it passes through an eye 15 arranged at the 15 end of a helical spring 16 which is always under tension. Thence the thread ascends inside the spindle 1 and issues through the porcelain eye 10, extends along the guide 9 and passes through the last eye before 20 coming to the work at the middle of the machine.

As the thread is used up by the machine, the eye 15 rises, so that the pawl 6^a may raise and at this instant allow the bobbin 25 to unwind a little.

Due to this arrangement, all the members, bobbins-guides and stops, have fixed positions with respect to each other, which assures the efficient operation of the device. 30 On the other hand, hitherto the bobbin, having no abutment at the top, tended to rise and prevent the disengagement of the pawl, which caused shocks and the breaking of the threads.

35 The cap 5 may have any suitable shape, and should be made as light as possible, well-balanced, and not exceeding the bobbin in diameter.

I claim as my invention—

40 1. In combination in bobbin carriers for braiding machines, a stationary spindle provided with a notch, a cap arranged on the spindle and having a tubular portion engaging the spindle and provided with a slot opposite said notch, a leaf spring connected to said cap and having a yoke-

shaped part embracing the tubular portion of the cap and provided with jaws to engage the notch for holding the cap upon the spindle, a thread bobbin loosely 50 mounted on the spindle and provided with a ratchet disc, thread guides supported by the cap and its tubular portion, and a pawl mounted on the cap and engaging the ratchet disk. 55

2. In combination in bobbin carriers for braiding machines, a stationary spindle having a notch near its upper end, a thread bobbin loosely mounted on said spindle and having a ratchet disk at its 60 upper portion, a cap provided with a tubular portion, mounted on the upper end of the spindle, the tubular portion having a slot arranged in alignment with the notch of the spindle, a leaf spring mounted on the cap and having its upper portion embracing the tubular portion of the cap and provided with jaws adapted to extend into the notch for holding the cap in position, thread guides mounted on the cap and 65 arranged at diametrically opposite sides of the same, and a pawl mounted on the cap and engaging the ratchet disk. 70

3. A combination as claimed in claim 2 in which one of said thread guides consists 75 of a resilient arm extending downwardly from the cap alongside of the bobbin and having an eye at its lower end, another thread guide arranged above said resilient arm and having an eye to permit the passage of the thread. 80

4. A combination as claimed in claim 2 in which the spindle is tubular and provided with a slot communicating with said notch, a lever movable with said pawl and passing through said slots into the spindle, said lever having a thread guide, and a spring arranged in the spindle and provided at its upper end with a thread guide. 85

In testimony whereof I hereunto affix my 90 signature.

HENRI FONTY.
